UNITED STATES PATENT OFFICE.

LOYD I. ALDRICH, OF PEORIA, ILLINOIS, ASSIGNOR TO HART OIL BURNER CO., OF PEORIA, ILLINOIS, A CORPORATION OF ILLINOIS.

LIQUID-FUEL ATOMIZER.

Application filed June 25, 1923. Serial No. 647,444.

To all whom it may concern:

Be it known that LOYD I. ALDRICH, citizen of the United States of America, residing at Peoria, in the county of Peoria and State of Illinois, has invented certain new and useful Improvements in Liquid-Fuel Atomizers, of which the following is a specification.

My invention relates to liquid fuel atomizers.

The object of my invention is in the provision of a liquid fuel atomizing device comprising a mechanical atomizing means operated by an electric motor and a series of electrical switches co-operating with the usual house thermostat for controlling the operation thereof.

Another object of my invention is in the particular adaptation and co-operation of a series of relay and safety control switches with a mechanical fuel burning means to produce an efficiently operating device.

Yet another object is my particular manner of relating the house thermostat to a furnace thermal control member whereby operation of the burner is controlled to prevent pre-ignition or rather pre-explosion.

A still further object is in the fashioning of a series of switches in co-operating high and low voltage circuits in connection with a house thermostat whereby a short circuiting of said thermostat will take place to prevent overheating by the low voltage current.

Still another object of my invention is in the particular fashioning of my relay and safety switches wherein a co-operation of elements results in an efficiency of operation and simplicity of structure.

Another object of my invention is in the provision of a mechanical connection between the fuel burning device and the main switch in the electrical circuit to insure the cutting out of said electrical circuit upon failure of operation of the burner.

Other objects of my invention will appear in the following specification taken in connection with the annexed drawings in which:

Figure 1 shows in elevation my fuel atomizer with the electrical control members therefor set out in diagram.

Figure 2 is a plan view of the main or relay switch and the safety switch.

Figure 3 is a plan view showing the

mounting of the transformer and spark coil.

Figure 4 is a perspective showing of the relay switch in detail.

Figure 5 is a side elevation of a portion of the mechanical connection between the fuel atomizer and the electrical circuit.

Figure 6 is a sectional view in detail of one of the solenoids in the relay switch.

In a former application for liquid fuel atomizing devices, Serial No. 633,272, filed April 19th, 1923, by applicant, there was a complete description of the fuel atomizing device shown in Figure 1 of the drawings. For the above reason, it is not thought necessary to again go into a detailed account of said portions but merely to state that by said mechanism an ignitable fuel mixture is formed and discharged into a combustion chamber. The only connection the present application has which might involve a description of portions of said burner is in a mechanical means connecting the burner with the electrical circuit, which will later be described. The present application is directed to the control means for said burner member, or rather, for the electrical motor which furnishes the power therefor. The burner member generally described as X has mounted there-above, a switch-board 10, attached to the burner by means of a bracket 11, integrally attached thereto. Upon this switch-board are mounted the various electrical switches, to be later described, and the electrical wiring therefor.

As is well known in the burner art, or rather the automatically operated burner art, a thermostat is mounted in a desirable part of the house and controls the operation of the burner thru a series of switches. The same result is accomplished in the present application; i. e. the control of the burner thru the house thermostat. However, in the present instance there are other results accomplished, due to the particular relationship of parts and fashioning of same.

A thermostat described as 12 and of usual construction is placed in the desired part of the house or other building that is to be heated by the burner.

I have not thought it necessary to show the burner as adapted for practical use and merely state that it is mounted similarly to other burners in the art which are inserted either into the ordinary house furnace or in-

to any other combustion chamber adapted for the use of liquid fuel heat.

In Figure 3 of the drawings is shown in plan a transformer 13 and spark coil 14.

- 5 These elements are of formal construction and for this reason a detailed description of their operation is not thought necessary. In Figure 2 is shown my special relay or main switch comprising the following parts:—A 10 bracket 16 is attached to the switch-board as at 17 and has pivoted thereto by means of a knife edge pivot 18, the main switch bar 19. The peculiar fashioning of this main switch bar is shown in detail in Figure 4 wherein 15 the contact end 20 thereof is shown as quite broad, the opposite end 21 merely being a single extending arm having at its outer end a lug 22 adapted to be engaged by a horizontally moving member to be later described. A second engagement lug 23 is also shown having connection with the arm 21.

20 As said before the contact end of the main switch is quite broad and pivoted with relation to this portion of the main switch are 25 the two subswitches 24 and 25 which are connected to the portion 20 by means of the coil springs 26 and 27 respectively. These subswitches 24 and 25 have the contact points 28 and 29 respectively thereon. The contact point 28 engaging a corresponding insulated terminal 30. The other subswitch 25 has its contact portion adapted to engage an opposed terminal 31 or short circuiting portion. For the purpose of later identification, I wish to term these subswitches circuit-breaking switch and short-circuiting switch respectively. The action of the main switch is clearly seen from observing Figure 4 of the drawings wherein the main switch 30 is pivoted upon the knife edge point 18 and the contact end thereof is adapted to make or break contact with the opposed contact point 32. In other words, when the contact end of the main switch is thrown upward it 35 makes contact between the points 20^a and 32 and at the same time, due to the action of the coil springs, the sub switches are thrown upward and make contact with the circuit-breaking and short-circuiting portions respectively; vice versa; when the switch is 40 thrown to its off position by mechanism to be hereafter described, the extended arm 21 of the switch is thrown upward with the result that the contact is broken between the points 45 20^a and 32, and similarly the downward movement of the contact portion of the switch thru the action of the coil springs 26 and 27 breaks the contacts between the circuit-breaker and short-circuiting portions.

50 The means for throwing the main switch from one position to the other is provided in the two solenoids 33 and 34 disposed directly beneath the main switch and adjacent its outer ends. These solenoids 33 and 34 55 are similar in construction, having windings

35 there-about, and slidable therein plungers 36 adapted to reciprocate in the cylindrical portions 37 of said solenoids. These plungers have stems 38 projecting thru the upper ends of the solenoid and adapted to engage 70 the under sides of the opposed ends of the main switch. Movement of these plungers within the solenoid is occasioned by the magnetizing of the coils there-about which produces upon such magnetizing an upward 75 movement of the plunger and a sustaining of such plunger in said upward position until the electric circuit to the coils is broken causing the release of the plunger. I have merely described one of these solenoids as 80 they are similar in construction and adapted to move the main or relay switch to the off or on position as desired. Disposed within both of the plungers in the solenoids are thermal or bi-metal strips 39 attached to the 85 plungers as at 40 and at their lower ends adapted or capable of engaging an insulated terminal 41. It might be said at this time that the contact between the thermal metal strip and the insulated terminals is only 90 made when the temperature, due to the heating of the solenoid coils, has caused considerable deflection of the thermal strips. The insulated terminals are connected by wires 42 and 43 to a magnetic coil 44, in a safety 95 switch mechanism now to be described.

95 This safety switch mechanism co-operates with the solenoids which are in the main switch mechanism and is formed of the following parts:—The magnetic coil 44 is attached to the switch-board as at 45 and has its magnetic surface 46 adjacent a pivoted arm 47 having a hooked lower end 48 adapted to engage a corresponding recess 49 in switch bar 50 pivoted at 51 to the 100 switch-board. The switch bar 50 carries an insulated contact portion 52 thereon adapted or capable of making contact with an adjacent opposed terminal 53. In briefly relating the thermal mechanism in the solenoid plunger to the safety switch, it might 105 be said that the extension of the thermal metal members, makes an electrical connection, whereby the magnetic coil 44 attracts the pivoted arm 47 with a resultant release 110 of the switch bar 50 and the breaking of contact between the opposed points 52 and 53.

115 Perhaps at this time it would be well to describe the ignition means for the fuel burner and its relation to the electrical switches above mentioned. The fuel mixture in the present structure is ignited by means of a gas flame, said gas flame likewise 120 being ignited by a spark mechanism. The whole ignition means operates but temporarily, or rather for a short period, upon the commencement of the operation of the device. Means for providing a spark to 125 ignite the gas pilot adjacent the discharge 130

opening of the burner, is provided in the spark coil 14, connected to a shunt around the solenoid or "on coil" 33. In other words, the primary circuit of the spark coil is connected to the wire on either side of the "on coil" to a spark coil energized and functioning only when the current is flowing thru the "on coil" and as we will see later, merely for a short period. The wire to the 10 sparking device, which is of formal construction, is shown at 54 and the gas tube from the usual supply at 55 being adapted to supply the ignition means for the gas pilot adjacent the sparking mechanism. 15 The above mechanism is well known, and my only reason for describing same is to bring in the co-ordination of the main switch or portions thereof to regulate the supply of gas thru the tube 55. 20 The above is accomplished in the following manner:—In Figure 2 of the drawings is shown the gas supply tube 55 adjacent the solenoid 33 of the main switch. This gas supply tube has a valve portion 56 25 therein, with the stem of the internally operated valve 57, extending downwardly therefrom and adapted to engage an arm 58 pivoted to the switchboard at 59 and engaging at its opposite end 60 the lower end 30 of the plunger 36 in the solenoid 33. As has been said before, the ignition mechanism operates but temporarily and of course this takes place upon the initial operation of the device which is at the time the main switch 35 is thrown to its "on" or rather upward position. The operation of the plunger in the solenoid 33 throws the contact end of the main switch upward and at the same time releases the valve 56 in the gas supply tube 40 55 permitting the flow of gas to the pilot adjacent the fuel discharge opening where it is ignited by the sparking mechanism. It may be clearly seen that the movement of the plunger 36 controls the gas supply 45 and consequently the ignition of the fuel.

In my co-pending application, upon the structural features of the present fuel burning device, I described the operation of the diaphragm 61, the raising and lowering of which, due to burner movement, acted in such manner as to control the supply of fuel to the burner. In other words, until a determined pressure was reached in the diaphragm, the fuel control valve would remain closed and likewise upon cessation of burner activity there would be a consequent shutting off of the fuel flow thereto.

My present application intends to relate the activity of this diaphragm to the main or relay switch before described; and in other words, to connect the mechanical portions of the burning device to the control switches by means of the following structure:

65 The diaphragm 61 thru its movement

forces upwardly or downwardly, the longitudinal arm 62 which has at its inner end a slip connection 63 with the arm 64 pivoted at 65 to the vertical lug 66. A substantially vertical lever 67 is pivoted to the outer end 70 of the arm 64 and tensioned with respect thereto by means of a small coil spring 68 engaging the hook portions 69 and 70 on the respective levers. This vertical lever 67 is adapted to reciprocate, influenced by movement of the diaphragm within the guide ways 71 and 72 attached to the switch board as at 73 and 74. In several of the figures in the drawings this arm or lever has been shown. In Figures 4 and 5 it is illustrated 80 in the clearest manner. In these figures the upper end of the lever is shown having the cam portion 75, and a roller 76 in the upper guide way is adapted to ride in this cam portion. In Figure 4 dotted and full line 85 views illustrate the peculiar action of this lever in its upward movement. As said before a small coil spring tends to force the upper end of the lever 67 toward the switch board. However, during the upward movement of the lever, due to relapse of the diaphragm, caused by cessation of motor activity, the roller 76 rides along the cam portion 75 and eventually, or rather after a determined distance, rides out of the cam 90 forcing the lever slightly outward. The purpose of this lever movement, is as shown in Figure 4, to raise the end 21 of the main switch; or in other words, to throw the main switch to its off position that is, breaking the 100 contact between the points 20^a and 32. The lever at its upper end abuts the lug 22 on the main switch and during its upward movement carries with it this end of the switch. However, when the roller 76 rides out of the 105 cam way the lever is thrown sufficiently outward to release the lug 22 on the main switch thereby leaving the main switch in such position that its normal pivotable movement will not be further restricted; or in other 110 words, permitting thereafter normal operation.

In Figure 1 of the drawings there is shown at 77 a thermal control member, or rather, furnace thermostat. This member is adapted to be mounted within the combustion chamber wherein the ignited fuel mixture is discharged. This furnace thermostat has been described in detail in my co-pending application No. 632,541 filed April 16th 115 1923 and briefly is made up of a thermal or bi-metal strip 78, the movement of which is controlled by temperature conditions within the combustion chamber and this movement is transmitted to a contact portion shown at 79. In other words, when the temperature within the combustion chamber is normal, contact is made therein and when the temperature rises upon ignition of the fuel mixture, the contact 79 is broken there being 120 125 130

means for timing the breaking of the contact relative to the rise in temperature.

The structural features of my electrical control portions have been set out and I now wish to describe the operations of the various switches with relation to the electric currents and operation of the burner. There are two electrical lines coming in from the street at 100 and 101 and a switch is located in each line. One of these switches is the relay or main switch and the other is the safety device operated by the heating of the thermal element in one of the magnets. These lines coming in from the street carry a high voltage current and the transformer takes this 110 volt current from both wires by forming a shunt from the main line which completes the circuit thru the electric motor. The wires taking this 110 volt current to the transformer are shown at 50 and 51.

Now since one of the connections of the transformer line is between the motor and the safety switch a breaking of the main line current by the safety switch stops the current flowing thru the transformer as well as thru the electric motor; in other words, making the entire outfit inactive. Hence we will see that both of the switches: i. e.; the main and safety switches in the 110 volt circuit must be closed in order that the motor or transformer functions.

The transformer 13 produces in its functioning, a low voltage current which we use to operate the relay or main switch before mentioned, thru a magnetizing of the solenoids 33 and 34; this current also being utilized to operate the magnet 44 and safety switch thru the heating of the thermal metal strip 39 in the plunger portion; the above operation being performed as follows:—

In case the voltage is maintained for a certain period thru one of the solenoids, it causes this solenoid to heat, this heating being in proportion to the length of time said current is flowing. The plunger which is movable within the solenoid carries therein the thermal or bi-metal strip 39. This strip, as said before, tends to bend when heated, this bending being in proportion to the degree of temperature to which it is subjected. The low voltage current from the transformer can flow only thru the safety magnet when this thermal strip is bent sufficiently to make contact with the insulated terminal 41 leading from this winding. In other words the bending of this thermal strip 39 in the solenoid closes the circuit thru the safety magnet winding which becomes energized and trips the pivoted lever 47 releasing the switch bar 50 thereby breaking the 110 volt or main line circuit which is carried by the wires 100 and 101. For the purpose of description, we will call the solenoid 33 the "on coil", from the fact that it

throws the main line switch to the "on" position. The other, the "off coil", from the fact that it dis-engages the main switch thereby stopping the motor and therefore the burner.

Taking the "on coil" circuit into consideration, we will trace the current as it is necessary to operate the burner. Leaving the transformer the current flows to the switch operated by the thermostat which is located in the desired portion of the house or other building, the temperature of which, we wish to control. This thermostat switch being closed, the current passes thru the same to the "on coil" thru its winding and to a switch which we call the "furnace thermostat", or furnace switch, which, if closed, allows the current to flow back to the transformer. Hence you will see there are two switches in this line, both of which must be closed in order that this coil 33 will become magnetized and operate the main switch. Also, this "on coil" 33 will remain energized and magnetized until one of these switches is opened. This "on coil" at the same time, when it throws the main switch into position, due to the upward movement of the plunger 36, also opens the gas valve thru connected mechanism which supplies the pilot flame for ignition purposes. We see thus that the gas valve will remain open as long as the solenoid or plunger is magnetized or rather held in its upper position.

We also have the spark coil 14 connected to a shunt around this "on coil". In other words, the primary circuit of the spark coil is connected thru the wires on either side of the "on coil" to a spark coil energized and functioning only when the current is flowing thru the "on coil", therefore, as long as the "on coil" is energized, the spark coil is producing a spark in its secondary winding and at its terminal adjacent the pilot gas flame which is also supplying gas while the "on coil" is energized.

This "on coil" will remain energized and magnetized until one of the switches: i. e.; either the thermostat or furnace switch is opened. Since the furnace switch opens upon the temperature in said furnace or combustion chamber rising due to the burning of the fuel mixture therein, it will be seen that immediately after the ignition of said fuel this furnace thermostat or switch will open, breaking the contact in the low voltage circuit and causing the plunger 36 in the "on coil" to drop back to the normal, or rather the lower, position occupied before the room thermostat closed the circuit causing the "on coil" to be energized.

In connection with the above description of the relationing of the thermostat and furnace switch with the main switch, it is desired to point out that if the temperature in the combustion chamber is sufficiently

high the furnace thermostat thru its relative parts will not close. Therefore, even if contact was made in the thermostat proper, there could be no energizing of the "on coil" and therefore the main switch could not be thrown to the run position and the outfit started. The object in relating the switches in the above mentioned manner is to prevent a starting of the outfit by manipulation of 5 the house thermostat before the brick work in the combustion chamber or furnace has cooled sufficiently to prevent preignition of the fuel mixture discharged therein, thus causing an explosion or so-called "puff" 10 which characterizes the ignition in most oil burning devices.

Also, it will be noted from the drawings that when the main switch is thrown to the run position it carries with it a pair of 20 movable contacts on the subswitches which move up against terminals insulated from the main switch. These subswitches serve, one as a circuit breaker and the other as a short-circuiting device. The operation of 25 the short circuiting device is as follows:—

When the main switch is thrown to the on position, the entire current necessary to operate the solenoid is flowing for an instant thru the room thermostat and if permitted 30 to flow thusly for any length of time it would be heated to such an extent that it would not function properly. However, when the main switch is thrown to its run position thru the action of the subswitches 35 there is a short circuiting thru the mediums above described, of the house thermostat and the current is short circuited directly from the transformer to the "on coil" thus cutting out the current flowing thru the thermostat on account of the resistance of the 40 wiring.

We will now consider the functioning of the "off coil" or solenoid 34, the principle of which is to throw the main switch open 45 when the temperature of the room rises to such an extent that it operates the switch in the room thermostat. The current which energizes this so-called "off coil" leaves the transformer flowing to the room thermostat 50 thru the switch thence thru the coil winding, thence thru an insulated post 30 where it makes contact with the subswitch or circuit breaking switch which is operated by the main switch. From the drawings it 55 will be seen that this circuit can be broken either by the main switch being thrown to its off position thus opening the circuit breaking switch, or by the temperature of the room falling to such an extent that it 60 opens the switch in the thermostat. Also, it will be seen that either one of these switches being open in this line will prevent the energizing of the solenoid or "off coil". The 65 action of the "off coil" is as follows:—

The circuit breaking switch is only closed

when the main switch is in its run position. The thermostat switch is closed because of the rising room temperature, and the current thus energizes the solenoid or "off coil" causing the plunger to rise, with the result 70 that the main switch is thrown to its off position. The main switch during such movement opens the circuit breaking switch stopping the flow of current thru the "off coil" and allowing the plunger therein to 75 drop back to its normal position so that it is out of the way of the main switch which may be moved thereafter by its being thrown to the on position by the closing of 80 the switches in the "on coil" circuit.

I have previously set out the operation of the lever 67 which connects the diaphragm 61 in the burner device with the main switch, said lever providing a means for cutting out the electrical connections to 85 the motor upon failure of the burner mechanism.

What I claim is:

1. In combination with a liquid fuel burner, automatic control means therefor including a primary electrical circuit having a main and safety switch therein, a secondary circuit adapted to operate said main switch, including a transformer house thermostat and furnace thermostat, and means including a subswitch for short circuiting 90 the house thermostat from the direct circuit upon initial switch movement.

2. In combination with a liquid fuel burner, automatic control means therefor including a main switch, means for operating said switch including a pair of solenoids, electric means for operating said solenoids to throw the switch in either direction and temperature control mechanism for operating the solenoids including a house thermostat and furnace thermostat. 100

3. In combination with a liquid fuel burner, automatic control means therefor, including a pivoted main switch, a pair of solenoids disposed thereunder and adapted upon being energized to throw said switch in either direction, and means for controlling the operation of said solenoids including 110 a house thermostat and furnace thermostat. 115

4. In combination with a liquid fuel burner, automatic control means therefor including a pivoted main switch, a pair of solenoids adapted to operate said switch, a house thermostat, a furnace thermostat controlling the operation of said solenoids and an ignition means for the burner including a gas and spark mechanism controlled by the operation of one of said solenoids. 120

5. In combination with a liquid fuel burner, automatic control means therefor, including a house thermostat, a main switch, a solenoid adapted to operate said switch, a safety switch, a thermal metal control member within said solenoid adapted under cer- 125 130

- tain conditions to operate said safety switch, and a temperature controlled switch located in the combustion chamber and capable upon rising temperatures of automatically cutting out said solenoid, and upon failure of combustion conditions, of permitting the extension of said thermal strip in the solenoid to release the safety switch.
6. In combination with a liquid fuel burner; automatic control means therefor, including a house thermostat, a pivoted main switch, a pair of solenoids adapted to operate said switch, a safety switch, thermal metal control strips disposed within the solenoids and adapted upon sufficient heating thereof to release said safety switch, and a temperature controlled switch mechanism located in the combustion chamber and capable under rising temperature conditions of automatically cutting out the solenoids prior to the operation of the safety switch.
7. In combination with a fuel oil burner, burner actuating mechanism, automatic control means for the burner, including a thermostat, a main switch adapted to be oper-

ated by the thermostat and controlling the activity of the burner, and means for returning the main switch to a starting position upon failure of burner activity at any time; said means including a member capable of moving the main switch to a starting position and an element movable upon initial movement of the actuating mechanism for controlling said member.

8. In combination with an electric motor driven fuel burner, an ignition member and safety mechanism comprising an electric circuit including in series a starting switch normally controlling the operation of the burner, an electrically operated switch actuating mechanism and contacts operated by a member sensitive to combustion conditions and a switch requiring manual reset adapted to be opened by the electrically operated switch actuating mechanism upon a failure of initial ignition or a failure of combustion conditions thereafter.

In testimony whereof, I affix my signature.

LOYD I. ALDRICH.
